UNITED STATES PATENT OFFICE

2,412,262

COVER

William Halpern, New York, Kurt Weiner,
Elmhurst, and Rudolf Krochmal, New York,
N. Y.

Application April 21, 1944, Serial No. 532,176

4 Claims. (Cl. 58—88)

1

The present invention relates to covers for watch faces.

One of its objects is to provide a watch cover construction which is self-closing.

Another object is to provide a watch cover construction that automatically maintains the cover in closed position without the aid of a catch or other locking device.

A further object is the provision of a watch cover construction which is easily opened without fumbling.

A still further object is the provision of a highly useful and ornamental watch cover opening construction which may very easily be made and which would be rather unlikely to go out of functioning order.

These and other objects are attained by mechanism comprising a pivoted watch face cover, a tensioning member operating to keep the cover in closed position on the watch, and an engaging member—generally a lever—to engage the watch cover and to raise it to its open position against the action of the tensioning member.

Preferred embodiments of the invention are shown in the drawings in which

Figure 1 is a side view of a watch incorporating the constructional features of one of said embodiments, showing the face cover thereof being manually held in raised or open position;

Figure 2 is a side view of the same watch showing the face cover in released or closed position;

Figure 3 is a side view of a modification of the construction shown in Figures 1 and 2.

Figure 4 is a top view of the same.

Figure 5 is a bottom view of the same.

Figure 6 is a longitudinal vertical section of the same.

Figure 7 is a horizontal section along the line 7—7 of Figure 6.

Figure 8 is a vertical section along the line 8—8 of Figure 6.

Referring to Figures 1 and 2 watch case 10 is provided with a hinged face cover 11 whose pivot or hinge pin 12 may be disposed on an axis parallel to the axis of the winding stem 13. Cover 11 is larger in width and length than watch case 10.

A coil spring 14 which is wound around pivot pin 12 engages cover 11 and watch case 10 and acts to keep cover 11 tight against watch case 10. A lever 15 which is pivoted, by means of a pivot pin 16 to frame work 17 in which the watch case 10 is set, engages with one end 18 the under surface of the over-hanging portion 19 of cover 11. The other end 20 of lever 15 is intended to be pressed down with the finger, thereby causing

2

its opposite end 18 to become elevated and thereby to raise cover 11 against the action of spring 14. Projecting piece 21 of framework 17 engages lever end 20 when the latter is fully released and when lever end 18 is in contact with over-hanging cover portion 19. Over-hanging portion 19 prevents, by virtue of the tension of spring 14, upward movement of lever end 18. Projecting piece 21 prevents upward movement of lever end 20. Lever 15 is thus rendered immobile. The lever 15 has the shape substantially of a bar, of which at least the inner end 18 is curved in the plane of rotation about the pivot pin 16 so as partially to circumscribe the pivot pin 12 of cover 11 while engaging the under side of cover 11. As the outer end 20 is depressed and the inner end 18 approaches the pivot pin 12, the area included within the curved end portion 18 thereby comes to include the pivot pin 12. The circumscribing construction 20 of the inner end portion 18, whereby it extends outwardly from cover pivot 12 of a straight line between the lever pivot pin 16 and the point of contact with cover 11, thus permits considerable displacement of the opposite end portions, 18, 20 within a relatively small space, combining mechanical compactness with novel and graceful appearance. By mounting lever 15 at a distance from case 10 additional leverage is furnished at the operative tip of inner end 18.

30 In the embodiment of the invention shown in Figures 3 to 8 inclusive, the single lever 15 has been replaced by the duplex lever 15c, comprising levers 15a and 15b, similar in all essentials to lever 15, and mounted on pivot 16 on opposite sides of the case 10. A tie bar 20c rigidly joins together the ends 20a and 20b of lever 15c. Pressure on either 20a or 20b now serves to depress both.

Advantages of this construction over the previous disclosure include an equalizing of strain on the pivots 12 and 16 and their bearings, and symmetrical appearance.

The tiebar 20c is shown most clearly in Figure 5. It will be understood that the tiebar is not readily apparent and its omission would not destroy the symmetrical appearance. If it were omitted the cover 11a could still be raised by pressure on either 20a or 20b as in the first disclosure.

50 Figure 7 illustrates the cover pivot 12 and spring 14 in open position, an arrangement used in the first, second and fourth forms of this invention, as indicated by the numerals ascribed to the fragmentary cover.

55 Figure 8 shows the cover and case in vertical

transverse section, including a downward extension 19a of the over-hanging portion 19.

It is apparent that the constructions shown above have been given solely by way of illustration and not by way of limitation, and that the illustrations above described are subject to wide variations and modifications within the scope and intent of the present invention. All of such variations and modifications are to be included within the scope of the present invention.

What is claimed is:

1. A watch face cover construction comprising, in combination with a watch case, a cover pivotally mounted on said case and comprising a portion overhanging said case, a spring acting upon said cover to maintain the same in closed position, and a substantially bar shaped lever, said lever having an inner portion adapted to engage said overhanging portion to open said cover, said inner portion extending from the pivot pin of said lever to said overhanging portion outwardly of a straight line between said pin and the point of contact of said lever with said overhanging portion and being curved substantially in the plane of rotation of said lever and partially circumscribing the pivot pin of said cover when the lever is depressed and the cover is raised.

2. A watch face cover construction comprising, in combination with a watch case, a cover pivotally mounted on said case and comprising a portion overhanging said case, a spring engaging said cover directly to maintain the same in closed position, and a substantially bar shaped lever, said

lever having an inner portion adapted to engage said overhanging portion to open said cover, said inner portion being curved substantially in the plane of rotation of said lever and partially circumscribing the pivot pin of said cover when the lever is depressed and the cover is raised.

3. A watch face cover construction comprising, in combination with a watch case, a cover pivotally mounted on said case and comprising a portion overhanging said case, a spring engaging said cover directly to maintain the same in closed position, and a substantially bar shaped lever, said lever being mounted at a distance from said case and having an inner portion adapted to engage said overhanging portion to open said cover, said inner portion being curved substantially in the plane of rotation of said lever and partially circumscribing the pivot pin of said cover when the lever is depressed and the cover is raised.

4. A watch face cover construction comprising, in combination with a watch case, a cover pivotally mounted on said case and comprising a portion overhanging said case, a spring arranged to normally maintain the cover in closed position, and a pivotally mounted lever, said lever having an inner portion adapted to engage said overhanging portion to open said cover, said inner portion being curved substantially in the plane of rotation of said lever and partially circumscribing the pivot pin of said cover when the lever is depressed and the cover is raised.
